UNITED STATES PATENT OFFICE.

GEORGE S. BARKENTIN, OF NEW BRITAIN, CONNECTICUT, ASSIGNOR TO THE CORBIN CABINET LOCK COMPANY, OF SAME PLACE.

DESIGN FOR ORNAMENTATION OF TRUNK-LOCKS.

SPECIFICATION forming part of Design No. 15 124, dated July 8, 1884

Application filed September 3, 1883. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for Ornamentation of a Trunk-Lock, of which the following is a specification, reference being had to the accompanying drawing, forming part thereof, 10 which drawing represents my design for a trunk-lock in front view.

The outer end of the part A is of circular form, and in the center of which is a circular panel containing the key-hole, and having fine lines crossing each other to divide the surface of said panel into small checks. Immediately surrounding this circular panel is a series of radiating leaflets, as shown. Outside of this central panel and leaflets is a larger circular panel inclosed by the raised ledge or border b, said panel having a sunken and roughened ground, and ornamented by the raised leaflets and conventional flowers, as shown. The portion between this circular end and the hinge 25 a contains a four-sided panel, the lower end of which is at right angles to the sides, while its upper end is curved inward, as shown, said panel being bordered by the plain raised ledge c, the upper end of which ledge also extends 30 around the raised ledge b of the circular panels. Within this panel, and extending lengthwise through the middle portion thereof, is a series of diamond-shaped ornaments, by the sides of which are raised parallel bars, as 35 shown. Upon the other side of said bars the panel is ornamented by conventional plants in relief. The other part, B, has a round hole in the center of its circular end, surrounding 40 which is a cluster of radiating leaflets, as shown. This orifice and leaflets form a central figure of the panel inclosed by a raised

ledge, d, the upper side of which is straight. Then it turns downward at right angles and merges into the circle, as shown. The surface of this panel is roughened and contains conventional plants by the side of the central ornament and partially inclosing the same. Substantially the whole border of both parts is beveled, and ornamented with conventional leaflets.

I claim:-

1. In the design for ornamentation of a trunk-lock herein shown and described, the circular panel containing the key-hole and surrounded by a series of radiating leaflets.

2. In the design for ornamentation of a trunk-lock herein shown and described, the circular panel inclosing the key-hole, the raised circular ledge b, and the conventional plants in relief between said ledge and the smaller circular panel.

3. The design for ornamentation of a trunk-lock herein shown and described, the same consisting of a panel and ornaments inclosed by the raised ledge b, the four-sided panel inclosed by the ledge c, and the beveled edge ornamented with leaflets.

4. The design for ornamentation of a trunk-lock herein shown and described, the same consisting of a circular panel containing the key-hole and surrounded by radiating leaflets, the surrounding sunken panel inclosed by a raised ledge, the four-sided panel with rounded end, and the part B, having a cluster of leaflets for its central ornament, and the surrounding panel inclosed by the ledge d, said panel being ornamented with conventional plants.

GEORGE S. BARKENTIN.
